DIAL TELEPHONE LOCK

Albert E. Feldman, New York, N. Y.

Application May 18, 1944, Serial No. 536,082

9 Claims. (Cl. 179—189)

This invention relates to dial telephone locks, and, more particularly, to an apparatus for preventing the unauthorized use of a telephone, which is operated by an oscillating dial.

Heretofore, locks of this character have been quite complicated in construction and, therefore, have been so expensive to manufacture that they have never attained widespread sale. It is an object of the present invention to provide a dial telephone locking apparatus which, although efficient for its intended purpose, comprises so few and simple parts that it can be marketed far below the price for which any previous locking devices could have been sold.

Other objects of the invention will in part be obvious and in part hereinafter pointed out.

The invention accordingly consists in the features of construction, combinations of elements and arrangement of parts which will be exemplified in the construction hereinafter described and of which the scope of application will be indicated in the appended claims.

In the accompanying drawings in which there is shown one of the various possible embodiments of the invention,

Fig. 1 is a side view of a dial telephone with an improved locking apparatus embodying my invention secured thereto;

Fig. 2 is an enlarged top plan view of said apparatus;

Fig. 3 is a sectional view taken substantially along the line 3—3 of Fig. 2;

Fig. 4 is a perspective view of a locking apparatus apart from a telephone;

Fig. 5 is a sectional view taken substantially along the line 5—5 of Fig. 2;

Fig. 6 is a view similar to Fig. 5 but shows the position of the locking parts after the key has been inserted;

Fig. 7 is a sectional view taken substantially along the line 7—7 of Fig. 5; and

Fig. 8 is an enlarged sectional view taken substantially along the line 8—8 of Fig. 2.

Referring now to the drawings, A denotes the base of a dial telephone whose receiver B is cradled thereon in conventional fashion.

The locking apparatus comprises an annular disc 10 having a central aperture 11. Said disc may be fabricated from a plastic material, as for example, a phenol condensate or cellulose acetate. The inner and outer rims of the disc have depending annular reinforcing ledges 12, 13 which, with the bottom surface of the disc, define a ring-like channel, best shown in section in Fig. 3. The locking disc is adapted to be superimposed upon

the oscillatable dial 14 of the telephone, leaving the rim thereof exposed. Said dial is mounted in conventional fashion on an oscillatable shaft 15 and is provided adjacent its circumference with a plurality of angularly spaced circular finger holes 16. The disc also has associated therewith the usual arcuate stop finger 17 which overlies an imperforate portion of the dial when the same is not being used. Said disc is so dimensioned in plan that it will substantially cover the annular zone of the dial in which the finger holes 16 are disposed, the identification plate 18 being visible through the disc aperture 11 which is seated on the bead surrounding said plate.

15 The bottom of the disc 10 has a recess 19 formed therein which extends through the ledges 12, 13, as well as the under surface of said disc to provide a seat for the curved stop finger 17 when said locking apparatus is coaxially disposed on the dial 14 in predetermined angular relation relative thereto.

20 This arrangement will prevent the dial from moving angularly relative to said finger if the disc is maintained in said position overlying the dial.

25 Means is provided on the disc for locking the disc to the dial in such fashion as to prevent either relative angular or axial movement thereof, that is to say, to prevent the disc from rotating about the dial or being lifted away there-

30 from except by an authorized person. Such means includes a post 20 of plastic material integrally secured to the under surface of the disc 10 and provided with a slot 21 adjacent its tip to form a jutting finger 22. The post and finger

35 are so disposed relative to the disc that when said finger is hooked through a predetermined finger hole, e. g. the finger hole over the numeral 3 in a conventional dial telephone and the disc is coaxially arranged relative to the telephone dial, the shank of the post will freely pass through the aforesaid finger hole and the tip of said finger 22 will underlie a portion of the dial adjacent said hole.

40 The locking means also includes another element disposed opposite and, preferably, substantially diametrically opposite to the post 20. This locking element must freely project through another finger hole 16 and have at least one locking member extending therefrom and underlying the dial, so as to prevent the disc from being pulled away from said dial. Pursuant to the invention, said member is biased to its extended position but may be retracted therefrom by proper but

45 simple use of an authorized key.

The locking element and member are constructed as follows: The disc 10 has a cup 24 integrally secured thereto in such position as to project through the finger hole diametrically opposite from that through which the post 20 extends. The side walls 25 of the cup have diametrically opposite slots 26 formed therein for almost their full length, said slots extending to the top of the disc. These slots snugly receive ribs 21 of a plug 28 which is fitted into the body of the cup 24 and is secured to the disc by a set screw 28a. Said plug is of such dimensions that its base 29 will clear the bottom 30 of the cup a predetermined amount to provide a space therebetween in which the locking member or members, soon to be described, are disposed. The plug has a knob 31 of any desired shape formed at its upper end. The plug and knob as well as the cup are made from plastic material.

It is desired to point out that the two pieces described, to wit, the disc 10 with its integral post 20 and cup 24, and the plug 28 with its associated knob 31, are all of simple contour, so that they may be readily fabricated at small expense by molding from conventional plastic materials and thus enable my locking apparatus to be manufactured at a very low cost.

In addition to these plastic parts, my improved locking apparatus also includes four small metal parts, two of which can be readily made from sheet metal by an inexpensive stamping operation, and the remaining two of which merely comprise light springs which can be purchased at extremely low cost in the open market.

The first two mentioned metal parts comprise two flat discs 32, 33 of which only one will be described in detail since they are of substantially identical construction. The rim of the disc 32 includes two oppositely disposed circular segments 34, 35, each having a radius of curvature equal to the internal radius of the cup 24. A tongue 36 extends from the periphery of the disc 32 in the center of one of the segments, e. g. the segment 34. Said tongue passes freely through one of the slots 26 and is long enough to protrude from the external surface of the cup 24 when the circular segment 34 is abutted against a side wall of the cup. The tongue at this time extends far enough beyond the side walls 25 of the cup to underlie a portion of the dial 14 surrounding the finger hole 16 through which the cup 24 freely projects (Fig. 5).

The two circular segments 34, 35 are so relatively arranged that when the disc is shifted across the cup and the other segment 35 abutted against the remote interior wall of said cup, the tip of the tongue 36 will be retracted far enough to permit the cup to be withdrawn through its associated finger hole 16. Preferably, the tongue is withdrawn far enough to bring its tip either into or closely adjacent the circumference of said cup (Fig. 6).

One of the discs, for example the disc 32, is slidably disposed against the base 29 of the plug 28 and the other disc 33 is slidably disposed upon the bottom 30 of the cup 24, the two discs being of such thickness that they substantially fill the space between the base of said plug and the bottom of said cup, and, therefore, slide upon one another. The disc 33 is faced in the opposite direction from the disc 32 (Fig. 7) so that its tongue 37 extends through the slot 26 opposite to the slot through which the tongue 36 projects.

Suitable means is provided to resiliently urge the discs to a position in which their tongues are fully outthrust from the cup. Said means comprises depending tangs 38, 39 (Fig. 5) struck from the cups. The tang 38 depends from the lower disc 33 and is freely slidably received in a channel 40 extending diametrically across the bottom 30 of the cup. The tang 39 depends from the upper disc 32 and, likewise, is freely received in said channel. Said last named tang 39 also passes through a diametrical slot 41 in the lower disc 33 which thus permits free relative movement of said two discs.

Each tang is disposed nearest the side wall 25 of the cup opposite to that through which the tongue of the disc carrying said tang projects. In the space between each of said tangs and the closest end of the channel 40, there is provided a small, light, helical compression spring 42 which biases the associated tang toward a position in which the tongue actuated thereby is fully extended from the cup.

The upper disc 32 also has a diametrical slot 43 oriented in the same manner as the slot 42 of the underlying disc 33. These slots are in alignment and partially overlap at the center of the discs 32, 33, as shown in Figs. 5, 6 and 7.

As mentioned earlier, the tongues 36, 37 can be retracted into the cup 24 by the simple and proper use of an authorized key 44. Said key may include a conventional handle having a straight-edged shank 46 on which is formed an axial bead and underlying groove 48. The tip 49 of the key is symmetrically tapered. The knob 31 and plug 28 have an axial key-hole slot 50 (Figs. 2 and 4) of cross-sectional configuration which is specially adapted to receive snugly a key having the particular contour just described, i. e. a flat straight-edged strip with an axial bead and underlying groove. The key-hole slot terminates at the base 29 of the plug 28 above the overlapping portions of the diametrical slots 42, 43. With this construction, when the key 44 is first inserted by simple translation in the key-hole 50, its tapered tip 49 will enter said overlapping portions. One tapered edge of the tip will engage the end of the slot 43 in the upper disc 32 remote from the tongue 36. The other tapered edge of the key tip will at the same time or shortly thereafter engage the end of the slot 41 in the underlying disc 33 remote from its tongue 37. As the key is pushed further in, the tapered edges of its tip will urge the discs together and thereby withdraw the tongues 36, 37 against the action of the compression springs 42. These springs are light enough, and the friction of the key in the key-hole 50 sufficient, to keep the tongues 36, 37 retracted as long as the key is left in the key-hole, without continually pressing the key down. It will be noted that the lock operates merely by insertion of the key without turning.

In the operation of the device, the finger 22 is first hooked through the finger hole 16 overlying the numeral 3. The key is then inserted in the key-hole 50, causing the tongues 36, 37 to retract. The cup 24 is now placed in the finger hole diametrically opposed to that through which the finger 22 was hooked. The key is then removed. This allows the tongues 36, 37 to spring outwardly under the influence of the compression springs 42 and lock the disc on the dial. The post and cup, together with the finger 22 and tongues 36, 37, will prevent the disc from rotating axially relative to the dial or being lifted away therefrom;

at the same time the recess 19 in the disc in which the stop finger 17 is seated will prevent the disc from rotating relative to the stop finger. Since the stop finger is fixed, the ultimate result is to prevent rotation of the dial relative to the finger stop as long as the disc is locked in position.

It will thus be seen that there is provided a device which achieves the several objects of this invention and which is well adapted to meet the conditions of practical use.

As various possible embodiments might be made of the above invention, and as various changes might be made in the embodiment above set forth, it is to be understood that all matter herein set forth or shown in the accompanying drawings is 15 to be interpreted as illustrative and not in a limiting sense.

Having thus described my invention, I claim as new and desire to secure by Letters Patent:

1. A locking apparatus for a dial telephone having an oscillatable dial with a plurality of finger holes therein and associated with an overlying stationary stop finger, said locking apparatus comprising a disc adapted to overlie said dial and leave the rim thereof exposed, said disc having a recess in its undersurface in which the stop finger is adapted to be seated, a member integrally depending from the undersurface of said disc and adapted to freely pass through one of the finger holes, a projecting finger on said member adapted to underlie a portion of the dial adjacent said finger hole, a second member opposite to said first named member and adapted to freely pass through another finger hole, an element supported by said second member and movable relative thereto between two positions in one of which it underlies a portion of the dial adjacent said second finger hole and in the other of which it clears said dial, means to bias said second member toward its first named position, and a key for moving said element from its first named to its second named position.

2. A locking apparatus for a dial telephone having an oscillatable dial with a plurality of finger holes therein and associated with an overlying stationary stop finger, said locking apparatus comprising a disc adapted to overlie said dial, said disc having a recess in its undersurface in which the stop finger is adapted to be seated, a member integrally depending from the undersurface of said disc and adapted to freely pass through one of the finger holes, a projecting finger on said member adapted to underlie a portion of the dial adjacent said finger hole, a second member opposite to said first named member and adapted to freely pass through another finger hole, an element supported by said second member and movable relative thereto between two positions in one of which it underlies a portion of the dial adjacent said second finger hole and in the other of which it clears said dial, means to bias said second member toward its first named position, and a key for moving said element from its first named to its second named position.

3. A locking apparatus for a dial telephone having an oscillatable dial with a plurality of finger holes therein and associated with an overlying stationary stop finger, said locking apparatus comprising a disc adapted to overlie said dial and leave the rim thereof exposed, said disc having a recess in its undersurface in which the stop finger is adapted to be seated, a member integrally depending from the undersurface of said disc and adapted to freely pass through one of the finger

holes, a projecting finger on said member adapted to underlie a portion of the dial adjacent said finger hole, a second member diametrically opposite to said first named member and adapted to freely pass through another finger hole, an element supported by said second member and movable relative thereto between two positions in one of which it underlies a portion of the dial adjacent said second finger hole and in the other of which it clears said dial, means to bias said second member toward its first named position, and a key for moving said element from its first named to its second named position.

4. A locking apparatus for a dial telephone having an oscillatable dial with a plurality of finger holes therein and associated with an overlying stationary stop finger, said locking apparatus comprising a disc adapted to overlie said dial, said disc having a recess in its undersurface in which the stop finger is adapted to be seated, a member integrally depending from the undersurface of said disc and adapted to freely pass through one of the finger holes, a projecting finger on said member adapted to underlie a portion of the dial adjacent said finger hole, a second member opposite to said first named member and adapted to freely pass through another finger hole, a pair of elements supported by said second member and each movable relative thereto between two positions in one of which each element underlies a portion of the dial adjacent said second finger hole and in the other of which each element clears said dial, means to bias said elements toward their first named positions, and a key for moving said elements from their first named position to their second named position.

5. A locking apparatus for a dial telephone having an oscillatable dial with a plurality of finger holes therein and associated with an overlying stationary stop finger, said locking apparatus comprising a disc adapted to overlie said dial, said disc having a recess in its undersurface in which the stop finger is adapted to be seated, a member integrally depending from the undersurface of said disc and adapted to freely pass through one of the finger holes, a projecting finger on said member adapted to underlie a portion of the dial adjacent said finger hole, a second member opposite to said first named member and adapted to freely pass through another finger hole, a pair of elements supported by said second member and each movable relative thereto between two positions in one of which each element underlies a portion of the dial adjacent said second finger hole and in the other of which each element clears said dial, means to bias said elements toward their first named positions, and a key having a tapered tip which is adapted to engage said elements upon simple insertion thereof and move said elements from their first to their second named positions.

6. A locking apparatus for a dial telephone having an oscillatable dial with a plurality of finger holes therein and associated with an overlying stationary stop finger, said locking apparatus comprising a disc adapted to overlie said dial and leave the rim thereof exposed, said disc having a recess in its undersurface in which the stop finger is adapted to be seated, a member integrally depending from the undersurface of said disc and adapted to freely pass through one of the finger holes, a projecting finger on said member adapted to underlie a portion of the dial adjacent said finger hole, a cup integrally depending from said disc and adapted to freely pass through an-

other finger hole, a pair of elements mounted for opposite slideable movement within said cup, each of said elements having a tongue adapted to project from said cup and extend out to underlie a portion of the dial adjacent said second finger hole when said elements are moved adjacent the side of the cup on which the tongues are disposed, a plug received in said cup to maintain said elements therein, said plug having a keyhole slot, a key adapted to be inserted in said slot and having cam surfaces on its end which are adapted to engage said elements and force them to a position in which their tongues extend from said cup in the manner aforesaid upon simple insertion of the key, and means to bias said elements toward a position in which said tongues are retracted.

7. A locking apparatus for a dial telephone having an oscillatable dial with a plurality of finger holes therein and associated with an overlying stationary stop finger, said locking apparatus comprising a disc adapted to overlie said dial and leave the rim thereof exposed, said disc having a recess in its undersurface in which the stop finger is adapted to be seated, a member integrally depending from the undersurface of said disc and adapted to freely pass through one of the finger holes, a projecting finger on said member adapted to underlie a portion of the dial adjacent said finger hole, a second member opposite the said first named member and adapted to freely pass through another finger hole, a key-operable element carried by said member and movable upon manipulation of said key to a position in which it underlies a portion of the dial adjacent said second finger hole, and means to bias said element to a position in which it is clear of the dial.

8. A locking apparatus for a dial telephone having an oscillatable dial with a plurality of finger holes therein and associated with an overlying stationary stop finger, said locking apparatus comprising a disc adapted to overlie said dial and leave the rim thereof exposed, said disc being

adapted to be seated on and in contact with the upper face of said dial and having a recess in its undersurface in which the stop finger is adapted to be received, a hook extending from the undersurface of said disc and adapted to be hooked through one of the finger holes, a member opposite to said hook and adapted to freely pass through another finger hole, an element carried by said member and movable between two positions in one of which it underlies a portion of the dial adjacent said second finger hole and in the other of which it is clear of said dial, means to bias said element toward said first named position, and key-operable means to move said element from its first named position to its second named position.

9. A locking apparatus for a dial telephone having an oscillatable dial with a plurality of finger holes therein and associated with an overlying stationary stop finger, said locking apparatus comprising a disc adapted to overlie said dial and leave the rim thereof exposed, said disc having a central aperture and being adapted to be seated on and in contact with the upper face of said dial with the dial identification plate extending into said aperture, said disc having a recess in its undersurface in which the stop finger is adapted to be received, a hook extending from the undersurface of said disc and adapted to be hooked through one of the finger holes, a member opposite to said hook and adapted to freely pass through another finger hole, an element carried by said member and movable between two positions in one of which it underlies a portion of the dial adjacent said second finger hole and in the other of which it is clear of said dial, means to bias said element toward said first named position, and key-operable means to move said element from its first named position to its second named position.

ALBERT E. FELDMAN.
